UNITED STATES PATENT OFFICE

154,876

DESIGN FOR A COMBINED VENT AND WALL COVER PLATE FOR OIL TANK INLET

Carl M. Preisinger, Cicero, and John E.
Svabek, Jr., Chicago, Ill.

Application April 10, 1947, Serial No. 138,288

Term of patent 14 years

(Cl. D52—2)

To all whom it may concern:

Be it known that we, Carl M. Preisinger and John E. Svabek, Jr., citizens of the United States, residing at Cicero and Chicago, in the county of Cook, and State of Illinois, respectively, have invented a new, original, and ornamental Design for a Combined Vent and Wall Cover Plate for Oil Tank Inlet, of which the following is a specification, reference being had to the accompanying drawing, forming part thereof.

Figure 1 is a front elevational view of the combined vent and wall cover plate for oil tank inlet showing my new design.

Figure 2 is a bottom view.

Figure 3 is a top plan view, and

Figure 4 is an end elevational view thereof.

The ends of the device are identical. The rear of the wall fitting is plain and unornamented.

The characteristic features of our design for the article disclosed reside in the ornamentation and configuration specifically as shown.

We claim:

The ornamental design for a combined vent and wall cover plate for oil tank inlet, substantially as shown and described.

CARL M. PREISINGER.
JOHN E. SVABEK, JR.
